CLAIM

We claim the ornamental design for a domed roasting oven, as shown and described.

DESCRIPTION

FIG. 1 is an isometric view of a domed roasting oven, showing my new design

FIG. 2 is a front elevation view thereof;

FIG. 3 is a top view thereof;

FIG. 4 is a left elevation view thereof;

FIG. 5 is a back view thereof;

FIG. 6 is a bottom view thereof;

FIG. 7 is an isometric view of the domed roasting oven, in which the domed lid is separated from the pan;

FIG. 8 is an isometric view of an interior of the domed lid and the pan, which form the domed roasting oven; and,

FIG. 9 is a cross-sectional side elevation view taken in the direction of the line 9-9 in FIG. 3.

The broken lines in the drawings depict portions of the domed roasting oven that form no part of the claimed design.
